UNITED STATES PATENT OFFICE

2,499,035

EMERGENCY EXIT

Logan P. Perkins, Sulphur, La.

Application May 28, 1947, Serial No. 750,969

1 Claim. (Cl. 254—159)

1

This invention relates to new and useful improvements in emergency exits, and the primary object of the present invention is to provide a device particularly adapted for use in high buildings, homes and the like that will permit a person to safely lower himself to the ground in a smooth, direct manner.

Another important object of the present invention is to provide a device of the character referred to including a governor mechanism that regulates the lowering of the person using the device so that his descent will be uninterrupted.

A further object of the present invention is to provide an emergency exit that is small and compact in structure so that the same may be quickly and readily attached to any building structure for instant use.

A still further aim of the present invention is to provide a device of the character described that is simple and practical in construction, strong and reliable in use, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of the emergency exit constructed in accordance with the present invention, with parts broken away and shown in section;

Figure 2 is a transverse vertical sectional view taken substantially on line 2—2 of Figure 1;

Figure 3 is a vertical sectional view taken on line 3—3 of Figure 1;

Figure 4 is a vertical sectional view taken on line 4—4 of Figure 1;

Figure 5 is a sectional view taken on line 5—5 of Figure 1;

Figure 6 is an enlarged detail view showing the manner in which the lugs mounted on the cable drum ride past the locking dogs when the cable drum is rotated without operation of the governor mechanism; and,

Figure 7 is an enlarged detail sectional view showing the manner in which the lugs mounted on the cable drum are locked against the locking dogs when the cable drum is rotated to effect an operation of the governor mechanism.

Referring now to the drawings in detail wherein, for the purpose of illustration, there is disclosed a preferred embodiment of the present invention, the numeral 10 represents a pair of up-

wardly and inwardly inclined side members or supports that are suitably secured to a substantially rectangular base plate 12.

Journalized between the supports is a shaft 14 on which is fixedly mounted a cable drum 18 which rotates with the shaft. The shaft carries collars 16 that limit the longitudinal movement of the shaft relative to the supports.

Secured to one of the supports and rotatably supporting one end of the shaft 14 is a stationary sleeve 20. A circular gear plate 22 is journalled for rotation on the shaft 14 and is interposed between the sleeve 20 and the cable drum 18. The gear plate is held spaced from the sleeve 20 by a suitable spacer collar 22a.

Secured to the sleeve 20 is a governor housing 24 in which brake shoes 26 are pivotally secured to an operating shaft 28 having an enlarged tubular extremity journaled in the side walls of housing 24, said brake shoes being oscillable to frictionally bear against the inner walls of the housing 24.

The enlarged tubular end includes a sleeve 30 carried by the housing, which sleeve is internally threaded at one end to receive a screw or the like 32. Slidably mounted in the sleeve is a plunger cap 34 that bears against the brake shoes 26, due to the urging from a coil spring 35 biased between the cap 34 and the screw 32.

Shaft 28 is journaled in a supporting bearing member 36 carried by the sleeve 30 and a pinion 38 is secured to the terminal portion of shaft 28 to engage the gear 22.

A plurality of circumferentially spaced pawls 40 are pivoted to plate 22, as at 22b, for engagement in arcuate slots 42 provided in the outer edge of a circular plate 44 that is integrally formed with the gear plate 22 which registers with one flanged portion 46 of the drum 18. On end of these pawls 40 is engaged by the free end of a spring arm 48 pivoted to plate 22 for normally retaining the pawls into the slots 42.

Pawls 40 are considerably thicker than the spring arms 48 and the lugs 50 are spaced laterally from the spring arms 48 so that the lugs will engage the pawls without contacting the spring arms.

In practical use of the device, a cable (not shown), wound on the drum, is attached to the waist of a person in any suitable manner. The person merely steps out of an elevated window, and as the cable drum is rotated to unwind the cable, the lugs 50 will engage the relatively straight end edges 50a of the pawls 40 to lock the drum to the gear 22 (see Figure 7) whereby

the gear 22 and the drum rotate as a unit. As the gear 22 rotates with the drum, the pinion 38, engaged with the gear 22, is rotated to actuate the governor mechanism.

A crank handle 52 is provided at one end of the shaft 14 for rewinding the cable on the drum. During this rewinding operation, the lugs 58 follow the contour of the inner curved edges 50b of the pawls to pivot the pawls and to permit the lugs to clear the pawls (as shown in Figure 6). Since during this operation, the lugs 58 do not lock against the pawls, the gear 22 will not rotate and the governor mechanism is inoperative, thereby increasing the durability of the governor mechanism.

Obviously, although only one governor mechanism designated generally by the numeral 24 is operatively connected to the cable drum 48, as shown in the drawings, other such mechanisms may be mounted on the base plate 12 and connected to the cable drum to increase the safety factor for the efficient operation of the emergency exit without departing from the scope of the present invention.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claim.

What I claim is:

An emergency exit comprising a base plate, a

pair of supports arising from said base plate, a stationary sleeve secured at one of its ends to one of said supports, a main shaft journalled for rotation on said supports and having a portion journalled for rotation in said sleeve, a governor mechanism carried by said sleeve and including an operating shaft, a gear journalled for rotation on said main shaft, a pinion on said operating shaft engaging said gear, a cable drum mounted on said main shaft for rotation therewith and including an end wall spaced from and in registry with said gear, a circular disk fixed to said gear and opposing the end wall of said drum, said disk having a plurality of circumferentially spaced recesses, a plurality of circumferentially spaced pawls pivoted to said gear and having corners received in said recesses, resilient means supported on said gear and yieldingly urging the corners of said pawls into said recesses, and a plurality of circumferentially spaced lugs on the end wall of said drum, said pawls having straight end edges for engaging the lugs to lock the drum to the gear for rotation of the gear and the drum as a unit during unwinding on the drum, said pawls having curved inner edges for engaging the lugs to permit the lugs to ride past the pawls during rewinding of the drum.
